UNITED STATES PATENT OFFICE

GEORGE S. WITHAM, SR., OF HUDSON FALLS, NEW YORK

PAPER MAKING MACHINE

Application filed July 11, 1929. Serial No. 377,373.

My invention relates to paper making machines, and more particularly to means and methods for forming a cut or slit automatically in a paper web for the purpose of preventing the extension or spreading of a tear 5 previously formed therein.

In the usual paper making machine, the paper web is formed upon a endless traveling screen known as a Fourdrinier screen, and the web thus formed is then passed between a pair of couch rolls and thence onto an endless felt conveyor which feeds the web between the several press and calender rolls. When the web passes from the Fourdrinier 10 screen to the first felt conveyor, the web is still somewhat damp and of little mechanical strength, so that it is not uncommon for breaks or tears to occur. When such a break or tear occurs, it usually extends from one side edge of the web inwardly and may result in the dropping of the torn portion of the web between the couch rolls and the felt conveyor. If this occurs, the tear continues to spread along the web which is being formed.

For the purpose of arresting the spread of such a tear, it has been common practice to intentionally form a cut or slit in the web, the cut extending from the longitudinal center line thereof diagonally to the side edge 25 adjacent which the tear is located. In this way a "lead strip" or "tail end" is formed which leads the web intact between the couch rolls, and the break or tear in the web is consequently confined to a small area.

One way of forming such an intentional cut or slit is to direct a fine, high velocity fluid jet upon the relatively soft web and to manually move the nozzle from which the jet emerges from the center of the web diagonally towards the side edge thereof adjacent which the break has formed. This method is subject to several disadvantages, the chief of which is that, since the web is traveling at an appreciable speed, a break, 40 when once started, will extend along the web for a considerable distance before an operator can reach the screen and form the tear-arresting slit.

An object of my invention is to overcome 45 this disadvantage through the provision of

a normally inactive nozzle located above the web and approximately midway between the side edges thereof, and means automatically operable when a tear or break forms on either side of the web for bringing the nozzle into action to emit a fluid jet to impinge upon and to cut the web; and at the same time to move the nozzle transversely of the direction of feed of the web and towards the side of the web having the tear so as to form a diagonal 55 slit and a resultant lead strip or tail end.

Other objects of the invention will become apparent from a reading of the following description, the appended claims, and the several views illustrated in the drawings, in 60 which:

Figure 1 is a central vertical longitudinal sectional view of a Fourdrinier screen and associated parts of a paper making machine, and showing my invention in connection 65 therewith;

Figure 2 is a view in elevation of a pair of suction boxes and associated vacuum pumps;

Figure 3 is a transverse vertical sectional view taken on the line 3—3 of Figure 1;

Figure 4 is a top plan view of the apparatus embodying my invention;

Figure 5 is a sectional view taken on the line 5—5 of Figure 1;

Figure 6 is a diagram of electrical connections;

Figure 7 is a detail view of a combined pressure gauge and switch;

Figure 8 is a detail view in front elevation of a mechanically operated switch; and

Figure 9 is a top plan view thereof.

In the drawings, the automatic web mending apparatus A embodying my invention is illustrated as used in connection with a paper web forming and feeding machine B of conventional design.

The web forming machine B includes a frame B', a Fourdrinier screen 1 mounted for continuous travel about the lower of two couch rolls 2 and guided by idler rolls 3. An 90 endless felt web feeder or conveyor 4 arranged to travel around rollers 5 is disposed in advance of the couch rolls 2 and in substantial alinement with the Fourdrinier screen. A paper web 6 formed on the Four- 95

drinier screen in the usual manner is led between the couch rolls 2 and thence onto the felt conveyor 4 between press rolls 7 and thence from the felt conveyor to another conveyor 7a which feeds the web to additional web treating machinery.

Referring to Figure 1, 6a designates a torn portion of the web which has fallen between the lower couch roll 2 and the adjacent roller 5 and 6^b and 6^c respectively represent the opposite side edges of the web. It is apparent that further feeding of the web to the right as viewed in Figure 1 will result in the tear in the web being extended indefinitely.

15 For automatically forming a cut in the web to intercept and arrest the extension of this tear, I provide a cutting device C, means D mounting the cutting device for movement transversely of the direction of feed of the 20 web, means E for moving the cutting device transversely in either direction, and controlling means F for automatically bringing the moving means into action when the web tears.

25 The cutting device C includes a normally inactive nozzle 12 adapted to discharge a fluid jet, a fixed fluid supply line 13 located centrally of the web, a flexible connection 14 between the nozzle and the supply line, and a 30 solenoid operated valve 14a for controlling the flow of fluid from the flexible connection to the nozzle. For mounting the nozzle for movements transversely of the direction of feed of the web, I provide the means D which 35 includes a pair of spaced parallel rods 15 disposed above and extending across the web transversely to the direction of feed and supported on the frame B' and a carriage 16 to which the valve and nozzle are attached, this 40 carriage being mounted on the rods for sliding movements transversely of the web in either direction.

45 The means E for moving the carriage and the nozzle transversely of the web includes a pair of sprocket wheels 17 and 17a disposed on opposite sides of the web and positioned approximately midway between the rods 15. These sprocket wheels are supported on 50 shafts 18 journaled in brackets 19 supported on the frame B'. An endless chain 20 is arranged to move about the sprocket wheels and is connected to the carriage 16 for moving the latter when the sprocket wheels are rotated. A reversible electric motor 21 carried 55 by the frame is arranged to rotate the sprocket wheel 17 by means of driving connections interposed between the latter and the motor, these driving connections including a shaft 22 journaled in a bracket 23 on the frame, co- 60 operating gears 24 and 25 respectively secured to the motor shaft and to the shaft 22, a clutch 26 interposed between the shaft 22 and the shaft 18, and a manually operable lever 27 for controlling the clutch.

65 It will be observed that when the motor is

rotated in one direction the chain 20 will move the carriage 16 and the nozzle 12 from the normal position adjacent the center of the web toward one side edge thereof, whereas, when the motor is rotated in the opposite direction, the carriage and the nozzle will be moved to the opposite side edge of the web.

In order that the nozzle will be automatically brought into action to discharge a fluid jet upon the web and also moved toward the side edge of the web adjacent which a tear has occurred, I have provided the automatic controlling means F which is associated with the motor and with the web, and is operable when a tear forms in the web to automatically open the solenoid valve to introduce water into the nozzle from the flexible connection 14, and also to automatically move the nozzle transversely of the web in the direction of the tear simultaneously with the continued feed of said web. To this end, it is necessary that either the motor be reversible or that, if it is desired to use a motor adapted to run in one direction only, reversing gears be interposed between the motor and the driven sprocket 17. In the present instance, I have illustrated a reversible motor of conventional type which is provided with three terminals. One of these terminals is connected to one side 28 of a power line through a conductor 29, and mechanically operated switches 30 and 31 which are interposed in this conductor are adapted, when open, to disconnect the motor from the side 28 of the power line for a purpose to be hereinafter described. One of the other motor terminals is adapted to be connected to the other side 32 of the power line through the medium of a conductor 33, and the remaining terminal is adapted to be connected to said side 32 of the line through the medium of a separate conductor 34.

The solenoid valve 14a for controlling the flow of fluid to the nozzle may be of any suitable type as regards its mechanical construction, and it is therefore unnecessary to show or describe the details thereof. It is, however, desirable that the solenoid include two separate coil windings 35 and 36 interposed respectively in the conductors 33 and 34 so that, when either of the coils is energized by the passage of a current through the associated conductor, the solenoid plunger will be moved to open the valve. Combined pressure gauges and electrical switches 37 and 38 are respectively interposed in the conductors 33 and 34 and are normally open so that current will not flow through the coils of the solenoid and the motor windings.

The switches 37 and 38 are adapted to be operated by fluid pressure by means to be later described, and each includes a casing 39, a stationary contact element 40 carried by the casing but insulated therefrom, a movable pressure responsive pointer 41 jour-

nalled for pivotal movements with respect to the casing but insulated therefrom, and a movable contact element 42 carried by the pointer and adapted, when the latter is rotated in a counter clockwise direction as viewed in Figure 7, to contact with the stationary element 40 and thus close the associated circuit.

From the foregoing, it will be observed that when the switch 37 is closed the coil 35 of the solenoid will be energized, thus opening the valve, and the motor will run in one direction, whereas, if the switch 38 is closed, the coil 36 will be energized to open the valve and the motor will be run in the other direction.

In order that the proper one of the switches 37 and 38 will be closed to move the nozzle in the direction of a break in the web, I provide a pair of suction boxes 43 and 44 positioned in cooperative relation to the web and preferably located in advance of the couch rolls. The suction boxes are arranged to extend respectively from opposite sides of the web to the longitudinal center line thereof, and each is provided with a perforated upper plate 45 over which the felt conveyor 4 carrying the web moves. Vacuum pumps 46 and 47 are respectively connected to the suction boxes 43 and 44 through the medium of pipes 48 and 49 for maintaining a vacuum in the suction boxes. The vacuum pumps are run at a constant speed so that the degree of vacuum within each of the suction boxes is dependent upon the continued existence of an unbroken web on the conveyor 4 above the top plates 45 of the boxes. It is apparent that, when a tear occurs in the web on either side of the center line thereof, this break will, when it passes over the associated suction box, result in the breaking of the vacuum therein. In order that this breaking of the vacuum be utilized to effect a closing of one of the switches 37-38, the suction box 43 is arranged to communicate with the pressure responsive pointer 41 in the gauge 37 by means of a pipe 50, and the suction box 44 is arranged to communicate with the pointer in the gauge 38 by means of a pipe 51. Thus, if a break occurs in the web between the center thereof and the left hand side edge as viewed in Figures 2 and 5, the vacuum will be broken in the suction box 43 and the pointer 41 of the valve 37 will be moved to bring the contact element 42 against the contact element 40, and the current will flow through the conductor 33 energizing the coil 35, thus opening the solenoid valve and at the same time starting the motor to run in a direction to move the nozzle 12 to the left as viewed in Figure 3. If, on the other hand, a break occurs on the other side of the web, the switch 38 will be closed, thus opening the valve in a similar manner and moving the nozzle transversely

of the web toward the right, as viewed in Figure 3.

It is desirable that means be provided for automatically closing the valve 15a and arresting the movement of the nozzle when the latter has been moved from its normal position to a point beyond the side edge of the web adjacent which a break has occurred. To this end each of the mechanically operated switches 30 and 31 is provided with a stationary contact element 52 carried by a bracket 53 supported on the frame A' but insulated therefrom, and a movable spring contact finger 54 secured at one end to an insulating block 55 on the bracket 53, and having a portion extending downwardly towards the chain 20, which portion is adapted to be engaged by a projection 56 on the chain. Thus, if the chain is moved to bring the projection 56 into engagement with the spring finger 54 of the switch 31, the finger will be moved away from the stationary contact 52 as illustrated in Figure 3, thus opening the connection between the motor and the side 28 of the power line, arresting the movement of the motor, and deenergizing the solenoid winding and closing the valve. In a similar manner, if the chain is moved in the opposite direction to bring the projection 56 into engagement with the movable finger of the switch 30, the latter will be opened, the motor stopped, and the valve closed.

For returning the nozzle to its normal position at the center of the web, I have provided a manually operable crank 57 attached to the sprocket wheel 17. When it is desired to return the nozzle to its normal position, the clutch 26 is disengaged by means of the manually operable lever 27 and the sprocket wheel 17 is then rotated by means of the crank.

Although the operation of the automatic web mending device described herein should be clear from the foregoing, it may be briefly stated as follows.

It is assumed that the web is traveling from the Fourdrinier screen toward the right as viewed in Figure 1, and thence on to the felt conveyor 4. If a break forms in the web, it is likely that the broken end will fall down between the couch rolls and the conveyor 4. Assuming that the break has occurred on the left hand side of the web as viewed in Figures 3 and 4, and at the back of Figure 1, the opening in the web left by the broken end 6a will, in time, pass over the suction box 43. This will result in the breaking of the vacuum therein so that the switch 37 will be closed, thus energizing the coil 35 and opening the valve to start the nozzle 12 to discharge a fluid jet upon the web, and simultaneously the motor will start to run in a direction to move the nozzle 12 toward the left as viewed in Figures 3 and 4 and toward the rear as viewed in Figure 1. In-

asmuch as the web is being fed, this movement of the nozzle will form a diagonal cut in the web which will extend from the center of the web to the side edge 6^c adjacent which 5 the tear has occurred. The "tail end" or "lead strip" thus formed will then lead the intact web through the couch rolls, and the torn portion 6^a which has thus been severed from the web will drop, and further spreading 10 of the tear will cease. When the nozzle has passed beyond the edge 6^c of the web adjacent which the tear occurred, the projection 56 on the chain will open the switch 30 and the valve will be closed and the motor 15 stopped. The operator will then disengage the clutch 26 and return the nozzle to its normal position by means of the crank 57. In a similar manner, if a break occurs on the other side edge 6^b of the web, the switch 38 will be 20 closed, the coil 36 will be energized to open the valve, and the motor will be run in a reverse direction and will thereby move the nozzle toward the right as viewed in Figures 3 and 4 and toward the front as viewed 25 in Figure 1. After the nozzle has passed beyond the side edge 6^b of the web, the switch 31 will be opened to close the valve and arrest the movement of the nozzle.

From the foregoing, it is apparent that, 30 through the provision of means for automatically arresting the progression or extension of a tear in a paper web, I have eliminated many of the disadvantages attendant with web mending devices formerly employed. 35 Even though the machine be not under the direct attention of an operator, the formation of a tear in a web will be so quickly corrected that there is no danger of the torn end of the web getting mixed in with or fouling the machinery. The device is simple in construction and therefore permits low cost installation and is of little trouble to operate and to maintain.

It will be observed that by my invention I 45 preserve the continuity of the sheet in a paper making machine when a break occurs by downwardly directing upon the moving sheet a jet of a squirt and automatically propelling the squirt over the sheet so as to intercept the break and form a lead strip and also that I downwardly direct upon the paper making wire a jet of a squirt and simultaneously automatically propel the squirt transversely over the sheet to sever the broken portion 50 before it completely parts the sheet, the combined movement of the sheet and squirt producing a gradually broadening lead strip.

I claim:

1. In a paper making machine, the combination with means for feeding a paper web; of means for cutting said web and adapted to be moved transversely of the direction of feed thereof; and means automatically operable when the web breaks for moving said 60 cutting means transversely of the web.

2. In a paper making machine, the combination with means for feeding a paper web; of means for cutting said web and adapted to be moved transversely of the direction of feed thereof; means for moving 70 said cutting means transversely of the web; and controlling means automatically operable when the web breaks for bringing said moving means into action to move said cutting means transversely of the web. 75

3. In a paper making machine, the combination with means for feeding a paper web; of means for cutting said web and adapted to be moved transversely of the direction of feed thereof, said means being 80 normally positioned approximately midway between the side edges of the web; means for moving said cutting means transversely of the web; and controlling means automatically operable when the web breaks on 85 one side of the longitudinal center thereof for bringing said moving means into action to move said cutting means transversely of the web in the direction of the break therein.

4. In a paper making machine, the combination with means for feeding a paper web; of means for cutting said web and adapted to be moved transversely of the direction of feed thereof, said means being normally positioned approximately midway between the 90 side edges of the web; means for moving said cutting means transversely of the web; and controlling means automatically operable when the web breaks on one side of the longitudinal center thereof for bringing said moving means into action to move said cutting means transversely of the web in the direction of the break therein. 95

5. In a paper making machine, the combination with means for feeding a paper web; of means for cutting said web and adapted to be 100 moved transversely of the direction of feed thereof, said means being normally positioned approximately midway between the side edges of the web; means for moving said cutting means transversely of the web; and controlling means having cooperative relation with the web between one side edge and the longitudinal center line thereof, and automatically operable when a portion of the web adjacent said controlling means breaks 110 for bringing said moving means into action to move said cutting means transversely of the web towards said side edge thereof. 115

6. In a paper making machine, the combination with means for feeding a paper web; of means for cutting said web and adapted to be moved transversely of the direction of feed thereof, said means being normally positioned approximately midway between the side edges of the web; means for 120

moving said cutting means transversely of the web; and separate controlling means respectively arranged in cooperative relation with the web on opposite sides of the longitudinal center line thereof, one of said controlling means being automatically operable when a portion of the web on one side of said center line and adjacent said means breaks for bringing said moving means into action to move said cutting means transversely of the web in the direction of the break, and the other of said controlling means being operable when the web breaks on the other side of the center line for bringing said moving means into action to move said cutting means in the direction of the break.

7. In a paper making machine, the combination with means for feeding a paper web; of means for cutting said web and adapted to be moved transversely of the direction of feed thereof; means for moving said cutting means transversely of the web; a suction box positioned for cooperation with said web; and pressure responsive means associated with said suction box and with said moving means and automatically operable upon the breaking of the vacuum in said suction box for bringing said moving means into action to move said cutting means transversely of the web.

8. In a paper making machine, the combination with means for feeding a paper web; of means for cutting said web and adapted to be moved transversely of the direction of feed thereof; means for moving said cutting means transversely of the web; a suction box positioned for cooperation with said web; pressure responsive means associated with said suction box and with said moving means and automatically operable upon the breaking of the vacuum in said suction box for bringing said moving means into action to move said cutting means transversely of the web; and means for automatically arresting the movement of said cutting means when the latter has passed beyond the edge of the web adjacent the break therein.

9. In a paper making machine, the combination with means for feeding a paper web; of means for cutting said web and adapted to be moved transversely of the direction of feed thereof, said means being normally positioned approximately midway between the side edges of the web; means for moving said cutting means transversely of the web; two suction boxes respectively positioned for cooperation with the portions of said web on opposite sides of the longitudinal center line thereof; and a pressure responsive means associated with each suction box and with said moving means, each of said pressure responsive means being automatically operable upon the breaking of the vacuum in the associated suction box for bringing said moving means into action to move said cutting means transversely of the web and across the side

portion thereof with which said suction box is associated.

10. In a paper making machine, the combination with means for feeding a paper web; of means for cutting said web and adapted to be moved transversely of the direction of feed thereof, said means being normally positioned approximately midway between the side edges of the web; means for moving said cutting means transversely of the web; two suction boxes respectively positioned for cooperation with the portions of said web on opposite sides of the longitudinal center line thereof; a pressure responsive means associated with each suction box and with said moving means, each of said pressure responsive means being automatically operable upon the breaking of the vacuum in the associated suction box for bringing said moving means into action to move said cutting means transversely of the web and across the side portion thereof with which said suction box is associated; and means for automatically arresting the movement of said cutting means when the latter has passed beyond the side edge of the web.

11. In a paper making machine, the combination with means for feeding a paper web; of means for cutting said web and adapted to be moved transversely of the direction of feed thereof, said means being normally positioned approximately midway between the side edges of the web; means for moving said cutting means transversely of the web; controlling means automatically operable when the web breaks on one side of the longitudinal center thereof for bringing said moving means into action to move said cutting means transversely of the web in the direction of the break therein and for automatically arresting the movement of said cutting means when the latter has passed beyond the edge of the web adjacent the break therein; and means for returning said cutting means to its normal position.

12. In a paper making machine, the combination with means for feeding a paper web; of means for cutting said web; movable means mounting said cutting means in cooperative relation to said web and for movements transversely of the direction of feed thereof, said cutting means being normally positioned approximately midway between the side edges of said web; a reversible motor; driving connections between said motor and said movable means; an electrical power supply line; electrical connections between said motor and said power line including a normally open switch adapted when closed to supply the motor with current to operate the motor to move said cutting means in one direction transversely of the direction of feed of the web, and a second normally open switch adapted when closed to operate the motor in the reverse direction to move said

cutting means in the opposite direction; and separate means in cooperative relation with the respective side portions of said web and adapted to close the respective switches, one of said means being operable for closing the 5 associated switch when the web breaks on one side of the center thereof and the other of said means being operable for closing the other switch when the web breaks on the opposite side of the center thereof.

13. In a paper making machine, the combination with means for feeding a paper web; of a normally inactive nozzle positioned in cooperative relation with the web and adapted to discharge a fluid jet upon said web to cut the latter, said nozzle being adapted to be moved transversely of the direction of feed of the web; and means automatically operable when the web breaks for moving said cutting means transversely of the web and for automatically bringing said nozzle into action to cut the web.

14. In a paper making machine, the combination with means for feeding a paper web; of a normally inactive nozzle positioned in cooperative relation with the web and adapted to discharge a fluid jet upon said web to cut the latter, said nozzle being adapted to be moved transversely of the direction of feed of the web; means for moving said nozzle transversely of the web; and controlling means automatically operable when the web breaks for bringing said moving means into action to move said nozzle transversely of the web and for automatically bringing said nozzle into action to cut the web.

15. In a paper making machine, the combination with means for feeding a paper web; of a normally inactive nozzle positioned in cooperative relation with the web and adapted to discharge a fluid jet upon said web to cut the latter and adapted to be moved transversely of the direction of feed of the web, said nozzle being normally positioned approximately midway between the side edges of the web; means for moving said nozzle transversely of the web; and controlling means automatically operable when the web breaks on one side of the longitudinal center thereof for bringing said moving means into action to move said nozzle transversely of the web in the direction of the break therein and for automatically bringing said nozzle into action to cut the web.

16. In a paper making machine, the combination with means for feeding a paper web; of a normally inactive nozzle positioned in cooperative relation with the web and adapted to discharge a fluid jet upon said web to cut the latter and adapted to be moved transversely of the direction of feed thereof, said nozzle being normally positioned approximately midway between the side edges of the web; means for moving said nozzle transversely of the web; and controlling means

automatically operable when the web breaks on one side of the longitudinal center thereof for bringing said moving means into action to move said nozzle transversely of the web in the direction of the break therein and for 70 automatically bringing said nozzle into action to cut the web and for automatically arresting the movement of said cutting means when the latter has passed beyond the edge of the web adjacent the break therein. 75

17. In a paper making machine, the combination with means for feeding a paper web; of a normally inactive nozzle positioned in cooperative relation with the web and adapted to discharge a fluid jet upon said web to cut 80 the latter and adapted to be moved transversely of the direction of feed thereof, said nozzle being normally positioned approximately midway between the side edges of the web; means for moving said nozzle transversely of the web; and controlling means having cooperative relation with the web between one side edge and the longitudinal center line thereof, and automatically operable when a portion of the web adjacent said 90 controlling means breaks for bringing said moving means into action to move said nozzle transversely of the web towards said side edge thereof and for automatically bringing said nozzle into action to cut the web. 95

18. In a paper making machine, the combination with means for feeding a paper web; of a normally inactive nozzle positioned in cooperative relation with the web and adapted to discharge a fluid jet upon said web to 100 cut the latter and adapted to be moved transversely of the direction of feed thereof, said nozzle being normally positioned approximately midway between the side edges of the web; means for moving said nozzle transversely of the web; and separate controlling means respectively arranged in cooperative relation with the web on opposite sides of the longitudinal center line thereof, one of said controlling means being automatically operable when a portion of the web on one side of 105 said center line and adjacent said means breaks for bringing said moving means into action to move said nozzle transversely of the web in the direction of the break and for automatically bringing said nozzle into action to cut the web, the other of said controlling means being operable when the web breaks on the other side of the center line for bringing said moving means into action to move said nozzle in the direction of the break and for automatically bringing said nozzle into action to cut the web. 110

19. In a paper making machine, the combination with means for feeding a paper web; of means for cutting said web and adapted to be moved transversely of the direction of feed thereof, said means being normally positioned approximately midway between the side edges of the web; means for 125

moving said cutting means transversely of the web; and controlling means automatically operable when the web breaks on one side of the longitudinal center thereof for bringing said moving means into action to move said cutting means transversely of the web in the direction of the break therein during continued feeding movement of the web and for automatically arresting the movement of said cutting means when the latter has passed beyond the edge of the web adjacent the break therein.

20. In a paper making machine, the combination with means for feeding a paper web; of means for cutting said web, said cutting means being normally positioned approximately midway between the side edges of the web and being movable in either direction transversely of the direction of feed of the web; and means automatically operable when the web breaks adjacent either side edge thereof for moving said cutting means transversely of the web in the direction of the break.

21. In a paper making machine, the combination with means for feeding a paper web; of a normally inactive nozzle positioned in cooperative relation to the web and adapted to discharge a fluid jet upon the web to cut the latter, said nozzle being movable transversely of the direction of feed of the web; a fixed fluid supply pipe; a flexible connection between said nozzle and said pipe; and web-controlled means operable when the web breaks for moving said nozzle transversely of the web and for admitting fluid from said pipe to said nozzle.

22. In a paper making machine, the combination with means for feeding a paper web; of normally stationary means for cutting said web and adapted to be moved transversely of the direction of feed thereof; means automatically operable when the web breaks for moving said cutting means transversely of the web; and means for returning said cutting means to its initial position.

23. In a paper making machine, the combination with means for feeding a paper web; of normally stationary means for cutting said web and adapted to be moved transversely of the direction of feed thereof; means automatically operable when the web breaks for moving said cutting means transversely of the web; and means for automatically arresting the movement of said cutting means when the latter has passed beyond the side edge of the web toward which said cutting means has been moved.

24. In a paper making machine, the combination with means for feeding a paper web; of normally stationary means for cutting said web and adapted to be moved transversely of the direction of feed thereof; means automatically operable when the web breaks for moving said cutting means transversely of the

web; means for automatically arresting the movement of said cutting means when the latter has passed beyond the side edge of the web toward which said cutting means has been moved; and means for returning said cutting means to its initial position.

25. In a paper making machine, the combination with means for feeding a paper web; of means for cutting said web and normally positioned approximately midway between the side edges thereof, said cutting means being adapted to be moved transversely in either direction of the direction of feed of the web; a reversible motor; driving connections between the cutting means and the motor; and means operable upon the tearing of the web at either side thereof for controlling said motor.

26. In a paper making machine, the combination with means for feeding a paper web; of means for cutting said web; movable means mounting said cutting means in cooperative relation to said web and for movements transversely of the direction of feed of the web, said movable means including a sprocket wheel positioned on each side of the web and an endless chain mounted on said sprocket wheels, said cutting means being secured to said chain and being normally positioned approximately midway between the side edges of the web; a motor, driving connections between the motor and one of the sprocket wheels; and means automatically operable when the web breaks adjacent either side edge thereof for operating the motor to move said cutting means transversely of the web in the direction of the break.

27. The method of preserving the continuity of the sheet in a paper making machine when a break occurs, which consists in downwardly directing upon the moving sheet a jet of a squirt and automatically propelling the squirt over the sheet so as to intercept the break and form a lead strip.

28. The method of preserving the continuity of the sheet in a paper making machine when a break occurs, which consists in downwardly directing upon the paper making wire a jet of a squirt and simultaneously automatically propelling the squirt transversely over the sheet to sever the broken portion before it completely parts the sheet, the combined movements of the sheet and squirt producing a gradually broadening lead strip.

In testimony whereof, I have hereunto subscribed my name.

GEORGE S. WITHAM, Sr.
